UNITED STATES PATENT OFFICE.

JOHN B. SINGER, OF WAYNOKA, OKLAHOMA, ASSIGNOR OF ONE-HALF TO JOSEPH W. SCOTT, OF WAYNOKA, OKLAHOMA.

COMBINATION WRENCH AND PLIERS.

Application filed July 2, 1921. Serial No. 482,132.

To all whom it may concern:

Be it known that I, JOHN B. SINGER, a citizen of the United States, residing at Waynoka, in the county of Woods and State 5 of Oklahoma, have invented certain new and useful Improvements in Combination Wrenches and Pliers, of which the following is a specification, reference being had to the accompanying drawings.

- 10 This invention relates to that kind of pliers or pipe tongs embodying a pair of crossing, lever-like handles having jaws, these handles being so pivoted together by means of a fulcrum pin or bolt working in a longitudinally extending slot that the jaws may be 15 adjusted within the limits determined by the length of the slot by sliding the handles edge-wise with reference to each other.

The general object of this invention is the 20 provision of a tool having opposed plier jaws at one end and alligator wrench jaws at the opposite end, these pliers being so adjustable that the jaws of the alligator wrench may be adjusted to suit objects of 25 different sizes.

A further object is to so form the alligator jaws and handles aforesaid that the jaws are firmly supported when in an object-engaging position, and that no strain will be brought 30 to bear on the bolt or pivot pin under these circumstances.

A further object is to form these alligator wrench jaws so that the confronting faces of the jaws gradually approach each other, thus 35 permitting a relatively large range of adjustments to be made.

Another object is to taper the jaws and set them at an angle to the handles so as to allow the alligator jaws to be inserted in a 40 very small place and yet retain their strength.

Other objects will appear in the course of the following description.

My invention is illustrated in the accompanying drawings, wherein:—

Figure 1 is a perspective view of my combination wrench;

Figure 2 is a top plan view of the wrench in one adjusted position;

Figure 3 is a top plan view of the wrench in another adjusted position;

Figure 4 is a plan view showing the wrench in still another adjusted position;

Figure 5 is a section on the line 5—5 of 55 Figure 2;

Referring to these drawings, it will be seen that my improved pliers or wrench consists of two members A and B. The member A is formed to provide a handle 10 and a jaw 11 which is angularly extended 60 with reference to the handle, the inner face of the jaw being cut away and toothed, as at 12, this jaw being formed adjacent its base with a wire receiving notch 13. The jaw is relatively thick at its outer end, as at 14, and 65 the extremity of the handle 10 is curved, as at 15, and tapered, and the concave or inner face of this angularly bent portion 15 is toothed, as at 16, to constitute the jaw of an alligator wrench. This portion 15 is relatively thicker than the handle 10 from the point 17 to the extremity of the jaw, this jaw portion 15 having a thickness equal to the thickened portion 14 on the extremity of the opposite jaw 11. Carried upon the 70 handle 10 at its junction with the jaw 11 is a pivot pin 18 which is reduced and screw-threaded at one end, as at 19, and at the other end formed with a head. A nut 20 engages the screw-threaded, reduced portion 80 19 of this pivot pin or bolt.

The member B is provided with a handle portion 21 which corresponds in length, thickness and width with the handle portion 10 of member A, and this handle 21 is widened, at 22, and formed with a longitudinally extending slot 23 enlarged at its middle and at its ends to form sockets 24. The extremity of the handle 21 is provided with a jaw 25 adapted to confront the jaw 11, the inner or concave face of this jaw being toothed, as at 26. The jaw 25 is thick relative to the handle 21, this thickened portion of the jaw being defined by the shoulder 27, and just inward of the shoulder 27 the 90 face of the jaw is cut away and formed with a cutting edge 28. This cutting edge shears across the notch 13. The opposite end of the handle 21 is angularly curved, as at 29, and its convex face is formed with ratchet teeth 30 which confront the ratchet teeth 16 of the portion 15. This jaw-like extremity of the handle portion 21 is also relatively thick, this thickened portion being defined by the shoulder 31.

In assembling the parts, the two members A and B are disposed against each other so that the two relatively thick jaws 15 and 29 will be in alignment and all lie 110 in the same plane, the pivot pin 18 then

being passed through the slot 23 and through the member A and fastened by a nut. This pivot pin, as illustrated in Figure 5, at its middle is formed with a relatively narrow shank 19^a rounded at the ends. The slot 23 has a width the width of the pin 19^a and this pin is disposed at such an angle with relation to the longitudinal axis of the handle 10 that the handle must be shifted to an angle of about 45° with the handle portion in order that the section B can be longitudinally shifted upon the section A. Of course, when the pin 19 is in any one of the sockets 24, the handle members can be oscillated with relation to each other, but when the handle members are closed, as in the clamping position of the tool, it is impossible to shift the sections A and B longitudinally with relation to each other.

20 By shifting the sections A and B with relation to each other, the jaws 11 and 25 may be adjusted to engage work of various sizes, but the particular construction of the jaws 11 and 25 forms no part of my invention, my invention residing in the combination with the jaws 11 and 25 of the jaws 16 and 29 and in the particular shape and relation of the jaws 16 and 29. It will be seen that the jaws 16 and 19 are tapered so that they may be readily inserted in relatively small spaces and that the confronting toothed faces 16 and 30 are divergently related to each other so that by longitudinally adjusting the members A and B with relation to each other, a large range of application of the wrench or pliers is secured. By forming the jaws 15 and 29 of the full thickness of the tool, that is forming these jaws with the shoulders 17 and 31, it will be obvious that strain placed upon these jaws will be transmitted to the shoulders and this strain will not be transmitted to the pivot pin or bolt 19. The handles 10 and 21 have the same width and are flat upon their confronting faces and rounded upon their outer faces so that the jaws, when closed or nearly closed, provide for a good grip.

50 The combination alligator wrench and plier which I have devised is extremely convenient, particularly for automobilists, and the combined wrench is adaptable for a large variety of purposes. It is obvious

that the design of the wrench may be changed in details without departing from the spirit of the invention as defined in the appended claims.

I claim:-

1. A wrench comprising two confronting members having pivotal and longitudinal sliding engagement with each other adjacent one end, this last named end being formed with opposed jaws, the remote end of each handle member being angularly extended in the same direction to form confronting alligator jaws, each jaw being thickened so as to overlie the other handle and the other jaw, the confronting faces of the jaws being toothed and having divergent relation to each other and each jaw being tapered toward its extremity.

2. A wrench of the character described comprising two confronting handle members, each formed at one extremity with an outwardly curved jaw, the jaws confronting each other, the end of each member remote from said first named jaws being angularly bent, the angular ends of the members extending in the same direction, each angular bent portion having a thickness equal to the thickness of both handle members whereby the last named jaws are disposed in the same plane, said last named jaws on their confronting faces being toothed, said toothed faces having an outwardly divergent relation to each other, one of said handle members being longitudinally slotted, the slot being enlarged to form a series of sockets along the length of the slot, and a fulcrum pin attached to the face of the other handle member and extending through the slot and having a diameter in one direction equal to the width of the slot and in a transverse direction greater than the width of the slot but less than the diameter of the sockets formed along the slots and the major axis of the pin being disposed at a longitudinal axis to the handle upon which it is mounted whereby said members can be turned into angular relation to each other to permit one of the members being longitudinally shifted upon the other member.

In testimony whereof I hereunto affix my signature.

JOHN B. SINGER.
